Attorney.

UNITED STATES PATENT OFFICE.

HERBERT MURRAY HARTE, OF MANCHESTER, ENGLAND.

PENCIL SHARPENER.

1,405,210.

Specification of Letters Patent.

Patented Jan. 31, 1922.

Application filed September 30, 1920, Serial No. 413,858. Renewed December 12, 1921. Serial No. 521,923

To all whom it may concern:

Be it known that I, HERBERT MURRAY HARTE, subject of the King of Great Britain and Ireland, and resident of Manchester, in the county of Lancaster, England, have invented certain Improvements in Pencil Sharpeners, of which the following is a specification.

This invention relates to improvements in pencil sharpeners, the object being to provide a device in which safety razor blades of the double-cutting or single edge type—and particularly such as have been discarded after use for shaving purposes—may be used as the pencil-sharpening medium.

With the aforesaid objects in view my invention comprises a hinged or clamping device in which the razor blade can be firmly held in the required cutting position combined with means for guiding the pencil to be sharpened with relation to the cutting blade and means for adjusting the latter to vary the keenness of the cut.

In the drawings—

Fig. 1. is a plan of the complete device in open form showing the blade in position, Fig. 2, plan of the device in the closed or using position.

Fig. 3, end elevation of same.

I provide a device preferably made of sheet metal but not confined to that material. The holder consists of two parts *a* and *b* hinged together at *c*, one of the parts being provided with upstanding projections *d* on to which the holes *e* in the razor blade *f* are passed. Three projections are shown in the drawings though the two outer ones are only necessary. The projections may be struck up from the plate material or consist of short studs riveted to the plate. They are substantially the same diameter as the holes in the razor blade *f* and are designed to hold the cutting edge of the latter in position. The second plate *b* is provided with holes *g* in register with the projections *d* when the holder is closed as in Fig. 2, the projections passing into the holes when the plate *b* is turned about the hinge *c* into the position shown in Fig. 2. In order to hold the blades firmly between the plates one of the latter *b* has pivoted to it at *h* a catch or clamp *i* adapted to enclose the free ends of the plates tightly. The engaging edges of

the clamp are bent apart slightly to enable this to be done.

Attached to or forming part of the plate *a* is a hollow conical tube *j* arranged adjacent to the cutting edge of the razor blade for the time being in use, such tube having a slit *k* at one side into which the cutting edge of the blade projects slightly. Such a conical tube is, of course, well known in pencil-sharpening devices. Its object is to receive and guide the pencil to be sharpened. Sharpening is effected by rotating the pencil against the cutting blade in the usual way, the shavings escaping through the slit *k*. The position of the conical tube is such that only a portion of the razor blade is in use at a time. That is to say one edge only where double edged blades are used. When one edge becomes dull, or a portion of said edge the blade can be turned over end to end or from side to side thus giving four different cutting edges.

The plates may be hinged at one side instead of at one end.

What I claim as my invention and desire to secure by Letters Patent is:—

1. A pencil sharpener, comprising two hinged plates, one of which has a conical guide arranged at one side of it and provided with a longitudinal slit, and a blade clamped between the said plates and provided with a cutting edge which projects into the said slit and sharpens the pencil when the pencil is revolved in the guide.

2. A pencil sharpener, comprising two hinged plates, one of which has a conical guide arranged at one side of it and provided with a longitudinal slit, one of the said plates having also projections which engage with holes in the other plate, and a blade provided with holes which also engage with the said projections, said blade being clamped between the said plates and provided with a cutting edge which projects into the said slit and sharpens the pencil when the pencil is revolved in the guide.

In testimony whereof I have hereunto set my hand in the presence of two witnesses.

HERBERT MURRAY HARTE.
Witnesses:

WILLIAM H. TAYLOR,
LILLIAN FAVELL.
